UNITED STATES PATENT OFFICE.

CHARLES POHL, OF LOS ANGELES, CALIFORNIA, ASSIGNOR OF ONE-HALF TO A. L. SHIPLEY, OF VENICE, CALIFORNIA.

STOOL.

Application filed February 16, 1922. Serial No. 536,894.

To all whom it may concern:

Be it known that I, CHARLES POHL, a citizen of the United States, residing at Los Angeles, in the county of Los Angeles and 5 State of California, have invented a new and useful Stool, of which the following is a specification.

This invention relates to a collapsible stool of which the various elements can be 10 assembled and disassembled, and an object of the invention is to secure a knock-down stool of great strength and rigidity.

Another object is to provide a construction that will enable anyone to very quickly 15 assemble or disassemble the various elements of the stool.

The accompanying drawings illustrate the invention.

Figure 1 is a perspective view of a stool 20 constructed in accordance with the provisions of this invention, a portion of the seat cover being broken away.

Fig. 2 is a sectional elevation of the stool.

Fig. 3 is an enlarged sectional detail of 25 one corner of the stool.

Fig. 4 is an enlarged sectional detail of the middle portion of the seat and the post.

Fig. 5 is an enlarged sectional detail of a portion of one of the legs and a portion of 30 one of the braces engaging the same.

Fig. 6 is an enlarged sectional detail of the lower portion of the post and the middle portions of the braces, showing the connection therebetween.

Fig. 7 is a plan view of the seat collapsed.

Fig. 8 is a longitudinal view, partly in section, of one of the legs.

Fig. 9 is a longitudinal view of one of the braces.

Fig. 10 is a longitudinal view of the inner post member.

Fig. 11 is a longitudinal view of the outer post member.

There is provided a seat 12 comprising 45 four side members 13 pivoted to one another at their ends as indicated at 14. Pivoted at 15 to the opposite side members 13 are crossed seat members 16 which are pivoted to one another at their centers as indicated at 17, thus the seat can be opened into the rectangular form shown in Figure 1, or folded into the collapsed condition shown in Fig. 7.

The pivots 14 project a substantial distance below the under faces of the members 55

13 and, when the seat parts are in position to form a rectangle, the pivots 14 are adapted to be received in the tubular upper ends of legs 18 which are preferably curved to a slight extent at their lower ends as indicated at 19.

The inner sides of the legs 18 are provided with slots 20 of sufficient length to admit the insertion into the slots of the ends of braces 21. There are two braces 21 and said braces 65 are arranged diagonally relative to the rectangular seat 12 and each brace is adapted to engage diagonally opposite legs 18. In order to prevent spreading apart of the legs 18, the braces 21 are provided near 70 their ends with notches 22 in their upper edges so as to hook beneath the upper edges of the slots 20.

The braces 21 are formed of strip spring metal and are shaped so that the middle 75 portions thereof lie at a right angle to the end portions to make the middle portions parallel with the seat members 16 which may also be of strip metal. The braces 21 are provided centrally with perforations 23. 80 The pivot 17 constitutes a tie rod as it is sufficiently long to extend from the seat 12 through the perforations 23 and project beneath the crossed braces 21. The pivot 17 passes loosely through perforations 171 in 85 the seat members 16 and is provided with a head 172 to seat against the upper face of the uppermost seat member 16. The pivot 17 is screw-threaded at its lower end, as indicated at 24, to receive a wing nut 25 90 which bears against the under brace 21 so as to force the braces upwardly to hold them with their notches 22 hooked securely into the legs 18 and to hold the legs and seat assembled.

Means are provided to limit upward motion of the middle portions of the braces 21 so that the legs 18 will not be bent inwardly toward one another when the wing nut 25 is tightened and, in this instance, there is 100 provided a tubular member 26 which constitutes a spacer. This member 26 constitutes the outer member of a post and the inner member of the post is formed by the pivot 17 which extends through the outer member. The upper end of the post member 26 bears against the under face of the under seat member 16 and the lower end of said post member seats upon the upper face of the upper brace 21. The member 26 is 110

preferably of such length that, when the wing nut 25 is tightened to hold the seat and braces toward one another, said braces will be slightly sprung or bowed upwardly 5 at their middle portions so as to be under tension. This tension tends to prevent the braces from disengaging the legs 18.

If desired, the seat 12 may be provided with a suitable fabric cover comprising a top 10 member 27 and side flanges 28 adapted to fit over the corners of the seat 12 so as to hold the cover in position on the seat.

Assuming that the stool is in the knock-down condition with the parts separated, as 15 indicated to a large extent in Figures 7 to 11 inclusive, to assemble the parts for constructing the stool, the seat 12 will be unfolded to form a rectangle and the pivot 17 will be passed through the perforations 171 20 in the members 16. The seat member will then be placed on a suitable support with the pivots 14 and 17 projecting upwardly. Then the spacer 26 will be slipped over the projecting end of the pivot 17 and the straight 25 ends of the legs 18 will be slipped over the pivots 14. Then the braces 21 will be placed with their perforations 23 engaging the projecting end of the pivot 17 and with their notches 22 engaging the legs 18. Then 30 the wing nut 25 will be applied to the post member 17 and tightened to slightly bow the braces upwardly and securely clamp them to the legs.

The stool will then be turned into upright 35 position. If it be desired to use the seat cover 27, said cover may be slipped over the seat 12. When the foregoing operations have been completed the parts will be as-

sembled as shown in Fig. 1. A reversal of the above described operations will place 40 the parts in the knock-down condition.

I claim:

1. In a stool, the combination of side seat members pivoted to one another at their ends, crossed seat members pivoted together 45 at their centers and pivoted to opposite side members, legs loosely supporting the ends of the side seat members, braces, and means detachably connecting the braces with the crossed seat members and holding the braces 50 engaged with the legs.

2. In a stool, the combination of side seat members pivoted to one another at their ends, crossed seat members pivoted together 55 at their centers and pivoted to opposite side members, a fabric cover on the seat members having side flanges fitting over the corners formed by the adjoining ends of the side members, and legs detachably supporting the side seat members.

3. In a stool, the combination of side seat members pivoted to one another at their ends, crossed seat members pivoted together 60 at their centers and pivoted to opposite side members, legs detachably engaging the pivots connecting the side seat members, and braces detachably connected with the legs, the pivot of the crossed seat members being 65 connected with the middle portions of the braces.

Signed at Los Angeles, California, this 7th day of February 1922,

CHARLES POHL

Witnesses:

GEORGE H. HILES,
L. BELLE WEAVER.
